(57) CLAIM

I claim the ornamental design for a brassiere strap kit, as shown and described.

DESCRIPTION

FIG. 1 is a front view of a brassiere strap kit showing my new design.

FIG. 2 is a rear side view of the claimed design.

FIG. 3 is a right side view of the claimed design.

FIG. 4 is a left side view of the claimed design.

FIG. 5 is a top view of the claimed design.

FIG. 6 is a bottom view of the claimed design; and, FIG. 7 is a perspective view of the claimed design in use. The broken lines appearing on FIG. 7 is environmental matter forming no part of the claimed design.
